UNITED STATES PATENT OFFICE.

LEVI L. HEIZER, OF NICHOLS, IOWA.

MARKING ATTACHMENT FOR CORN-PLANTERS.

1,267,546.

Specification of Letters Patent. Patented May 28, 1918.

Application filed August 2, 1917. Serial No. 184,116.

To all whom it may concern:

Be it known that I, LEVI L. HEIZER, a citizen of the United States, residing at Nichols, in the county of Muscatine and State of Iowa, have invented certain new and useful Improvements in Marking Attachments for Corn-Planters; and I do declare the following to be a full, clear, and exact description of the invention, such as will enable others skilled in the art to which it appertains, to make and use the same.

My invention relates to improvements in marking devices for corn planters and the like and the principal object is to so improve upon the construction and mounting of such markers as to permit them to be readily swung to either side of the machine without interfering in any manner with other parts.

A still further object of the invention is to provide novel means whereby the marker may be easily attached and detached whenever required.

With the foregoing general objects in view, the invention resides in the novel features of construction and unique combinations of parts to be hereinafter fully described and claimed, the descriptive matter being supplemented by the accompanying drawings which form a part of this specification and in which:

Figure 1 is a top plan view of the invention applied;

Fig. 2 is a transverse view of the attachment removed from the corn planter; and,

Fig. 3 is a detail longitudinal section.

In the drawings above briefly described, the numeral 1 has reference to a suitable bracket which is secured by clips or the like 2, to the rear end of a corn planter frame, said bracket being by preference formed of a single metal bar whose intermediate portion is bowed rearwardly as indicated at 3 to serve as a pivotal mounting for a clamp or the like 4 by means of which the usual marking rod 5 is connected to the machine, the outer end of said rod having a marking disk or any other preferred type of marking instrument as indicated at 6. Heretofore, difficulty has been experienced when shifting the marking rod 5 from one side of the machine to the other, and the means heretofore provided for attaching and detaching the marker has in most cases included a number of parts which

were easily lost when detached. Due to the nature of the present invention, however, there are no loose parts which may be misplaced, and the marker may be freely 60 swung from side to side as occasion may demand.

In detachably connecting the clamp 4 to the bracket 1, said clamp is provided with a pivot pin 7 which passes through alined 65 openings in the portion 3 of said bracket and in a cross bar 8 which extends across said portion, said pin having a transverse notch 9 in which a latch 10 is receivable, said latch being pivoted to the bar 8 or to 70 any other preferred part of the device, so that there is no danger whatever of losing the same. When the latch 10 is in operative position, the pin 7 may not be removed, but when detachment of said pin is necessary, 75 raising of the latch 10 will permit such detachment.

Positioned in a plane in advance of the clamp 4, is a transversely disposed arched rod 11 having one end anchored in an eye 80 12 on one end of the bracket 1, whereas the other end of said rod is detachably received in a hook-like keeper 13 carried by the other end of the bracket, said last named end of the rod being provided with stops 85 14 above and below the keeper to hold it against vertical movement. Similar stops 15 are provided above and below the eye 12 to prevent shifting of the arched rod 11 yet at the same time to permit a pivotal 90 movement thereof when it is disengaged from the keeper 13. The rod 11 receives thereon an elongated guide 16 which is connected loosely with the inner end of a brace rod 17, the outer end of this rod being 95 secured in any preferred manner, as by a clamp 18, to the marking rod 5, so that the latter will be braced against rearward swinging. It will be observed that the loose connection between the guide 16 and 100 the rod 17, will prevent possible bending of the latter when backing the planter whenever required.

By the features of construction above described, whenever the marking rod 5 is 105 swung from one side of the machine to the other, the guide 16 will follow along the arched rod 11, without interfering in any manner with any of the other parts of the machine. Furthermore, whenever the marker 110 is to be detached, the latch 10 may be actuated to release the pivot pin 7, whereupon

the entire clamp 4 may be removed. Furthermore, either after or before removal of the clamp in question, the rod 11 may be disengaged from the keeper 13, so that the 5 guide 16 may move from the released end of said rod, thus detaching the entire marker from the planter frame. After such detachment, the rod 11 will be again snapped into the keeper 13 and will so remain until the 10 marker is to be again applied. When this occasion arises, the attachment of the formerly removed parts, is simply a reversal of the removal operation as will be readily understood.

15 From the foregoing, taken in connection with the accompanying drawings, it will be obvious that although the device is of comparatively simple and inexpensive construction, it will be highly efficient and durable for the purposes intended. Furthermore, the attachment may be employed in connection with numerous types of planters and it will be obvious that numerous minor details of construction may be varied to meet 20 the requirements.

25 I claim:—

1. In a marking attachment for planters, the combination of a marking rod and means for pivoting it to the planter for 30 swinging to either side thereof, a brace for said rod having a guide, an arched rod on which said guide is slidable, means for anchoring one end of said rod to the planter, a laterally opening hook to detachably connect the other end of said rod with the 35 planter, means for securing said hook to said planter, and shoulders on said rod above and below said hook.

2. In combination with a marking attachment 40 for a planter, a bracket comprising a horizontal bar having its intermediate portion bowed laterally, means for securing the ends of said bar to the rear end of the planter frame, a marker pivotally mounted on said rearwardly bowed portion of said bar, a brace for said marker having at its inner end a guide, an arched rod upon which said guide is mounted slidably, one end of said rod being anchored to one end of said 45 bar, and a hook-like keeper formed on the other end of said bar for detachably receiving the remaining end of said rod, said guide being removable from said rod when the last named end thereof is disengaged 50 from said seat.

55 3. In combination with a marking attachment for a planter, a bracket comprising a horizontal bar having its intermediate portion bowed laterally, means for securing the 60 ends of said bar to the rear end of the

planter frame, a brace rod disposed between the outwardly bowed arms of said bracket, said brace bar and said bracket being provided with aligned apertures, a marker having one end pivotally mounted between the 65 arms of the frame provided with a pivot pin extending through said apertures, a pivoted catch on said brace bar for engaging the inner ends of said pivot pin thereby locking the marker to the planter, an arched 70 rod secured to said bracket and a brace for said marker having a guide mounted on said arched rod for movement along the same when the marker is reversed.

4. In combination with a marking attachment 75 for a planter, a bracket comprising a horizontal bar having its intermediate portion bowed laterally, means for securing the ends of said bar to the rear end of the planter frame, a brace rod disposed between the outwardly bowed arms of said bracket, said brace bar and said bracket being provided with aligned apertures, a marker having one end pivotally mounted between the 80 arms of the frame provided with a pivot pin extending through said apertures, a pivoted catch on said brace bar for engaging the inner ends of said pivot pin thereby locking the marker to the planter, a brace for said marker having at its inner end a 85 guide, an arched rod upon which said guide is slidably mounted, one side of said rod being anchored to one end of said bar and a hook like keeper formed on the other end of said bar for detachably connecting the 90 remaining ends of said rod, said guide being removable from said rod when said last mentioned end is disengaged from said seat.

5. In a marking attachment for corn 95 planters, the combination of a marking rod 100 and means for pivoting it to the planter for swinging to either side thereof, a brace for said rod having a guide, an arched rod on which said guide is slidable, an eye in which one end of said rod is received for horizontal 105 swinging and means for securing said eye to the planter frame, an inwardly opening hook into which the other end of said rod is sprung and held by the resiliency of said rod, means for securing said hook to the planter frame, and shoulders on said rod above and below said hook.

In testimony whereof I have hereunto set my hand in the presence of two subscribing witnesses.

LEVI L. HEIZER.
